LOCK

Filed Oct. 20, 1938

UNITED STATES PATENT OFFICE

2,301,558

LOCK

Rollo Marple, Jackson, Mich., assignor to Hancock Manufacturing Company, Jackson, Mich., a corporation of Michigan

Application October 20, 1938, Serial No. 235,983

8 Claims. (Cl. 292—164)

The present invention relates to locking devices for closures, and in the specific embodiment herein disclosed, is directed particularly to the provision of improved locking devices for automobile doors.

The principal objects of the present invention are to provide improved locking devices particularly adapted for but not limited to use in connection with vehicle doors; to provide such locking devices which are simple in construction, economical of manufacture, and which are reliable and efficient in operation; to provide such devices embodying improved constructions of locking devices for preventing releasing movements of the bolt; to provide such devices embodying a bolt selectively releasable from engaging relation to an associated keeper, a member movably associated with the lock casing and responsive to either an inside or an outside handle for releasing the bolt, and locking means selectively engageable with the just-mentioned member for preventing operation of the bolt by either the inside or the outside handle; to provide such devices wherein a releasing movement of the bolt, occasioned, for example, by a closing movement of the door, serves to release the locking device from locking position; and to provide such devices embodying improved supporting and cushioning relationship between the movable parts of the lock.

With the above as well as other and more detailed objects in view, which appear in the following description and in the appended claims, preferred but illustrative embodiments of the invention are shown in the accompanying drawing, throughout the several views of which corresponding reference characters are used to designate corresponding parts, and in which:

Figure 1 is a view in elevation of one embodiment of the invention;

Fig. 2 is a view in horizontal section, taken along the line 2—2 of Fig. 1;

Fig. 3 is a view in elevation of a modified embodiment of the invention;

Fig. 4 is a view in horizontal section, taken along the line 4—4 of Fig. 3; and

Fig. 5 is a view in vertical section, taken along the line 5—5 of Fig. 3;

Referring first to the embodiment of Figs. 1 and 2, the therein described door lock comprises a case plate 10, a bolt 12, a retracting member 14, an outside operated rollback member 16, an inside operated link 18 which may, as will be appreciated, be connected to the usual inside handle 55

(not shown), and a selectively operable locking device designated as a whole as 20.

The bolt 12 is illustrated herein as being of the 5 slidable type, having a thickened nose 22, which projects through an opening provided therefor in the flange 24 of the case plate. It will be understood that in the more generic aspects of the invention bolt actions of other types may be used, such, for example, as those disclosed in applicant's copending application Serial No. 235,982, filed October 20, 1938, and in applicant's copending application Serial No. 236,135, filed October 21, 1938.

Continuing with the description of the present 15 embodiment, a usual coil spring 26, which is secured to the base 28 of the case plate, bears against the rear face 30 of the bolt head 22, and so continuously urges the latter to the left, as viewed in Fig. 1, to a fully projected position, in 20 which the nose 22 of the bolt is adapted to cooperate with a suitable lock keeper (not shown). The body of the bolt 12, which is preferably formed as a metal stamping suitably secured to the head 22, extends rearwardly from the head 25 22, and lies generally parallel to but in spaced relation to the base 28 of the case plate 10. Adjacent its rear end, the bolt 12 is provided with a longitudinally extending slot 32, which receives a guide pin 34. One end of the guide pin 34 is 30 riveted to the base of the case plate, and the other end thereof is correspondingly secured to a supplemental casing member 36. The guide pin 34 is thus fixed in position relative to the case plate, and acts to give guiding support to the 35 rear end of the bolt 12 during the sliding movements thereof. Additional guiding support for the bolt is provided by the opening provided therefor in the case plate flange 24. The bolt is also provided with a downwardly positioned 40 laterally projecting foot 38, which cooperates, as hereinafter described, with a rubber buffer 40 carried by the previously mentioned actuating slide 14 to effect retracting movements of the bolt.

45 The outside rollback, designated as a whole as 16, is constructed in accordance with the arrangement disclosed and claimed in Moore Patent 1,895,893, assigned to the same assignee as the present application, and comprises two 50 rollback elements 42 and 44, each whereof is provided with a squared opening to receive the usual squared spindle 46, to which the outside handle may be connected. The squared opening in the rollback elements 42 and 44 are slightly angularly offset with respect to each other. The

rollback element 44 is provided with a nose 44a, which is positioned to abut the flange 24. The rollback element 42 is provided with a nose 48, which is disposed to be normally engaged by a foot 50 formed on the slide 14, and urged thereby in a counterclockwise direction of rotation as viewed in Fig. 1. With this relation, it will be appreciated that the rollback elements 42 and 44 have a scissor action upon the spindle 46, and so wedgingly hold the latter against rattling within the squared openings. The rollback element 42 is also provided with a downwardly extending foot 52, which is disposed to cooperate with a key controlled locking slide, such as 54, to enable the door to be locked from the outside. The key slide 54 may be conventionally arranged to be selectively moved upwardly from the retracted position shown in dotted lines to a position in blocking relation to the foot 52. The actuating parts for the key slide 54 may be conventional and are not shown herein. The rollback elements 42 and 44 are provided with axially extending projections 42a and 44b, by which they are rotatably mounted in the base 28 of the case plate and in a corresponding opening provided in a supplemental casing member 56, which is secured to the base of the case plate adjacent the lower edge thereof.

The slide 14 comprises a longitudinally extending body, which is positioned between the rearwardly extending bolt body and the base 28 of the case plate, and is guided thereon by a shoulder 58 secured to the base of the case plate and the previously mentioned guide pin 34. The guide pin 34 rides in a slot 60 formed in the slide 14. The slide 14 is also provided with a laterally turned foot 62, which acts as a back-up support for the previously mentioned rubber block 40. The block 40 is secured to the slide 14 by a rivet 64 or equivalent means.

The slide 14 serves to normally urge the outside rollback element 42 in a counter-clockwise direction, as previously mentioned, and for this purpose the slide 14 is provided with a coil spring 66, the free end whereof bears against a projection 68 which extends upwardly from the body of the slide.

In addition, to adapt it for cooperation with the previously mentioned locking device 20, the slide 14 is provided with an additional upwardly projecting abutment 70.

In accordance with the present embodiment, the locking device 20 comprises a roller 72, the main body portion whereof is positioned for vertical sliding movement between the supplemental casing member 36 and the base 28 of the case plate. The reduced ends, such as 74, of the roller 72 ride in elongated slots such as 76 formed in the casing member 36 and in the base 28. The roller 72 is also provided with a bore, within which the laterally turned end of a control rod 78 is secured. With this relation, it will be understood that the control rod 78 may be suitably controlled, as by means of a button (not shown) available from within the associated vehicle, so as to move the locking roller 72 from the lower or locking position shown in Fig. 1, to a raised position, in which it is out of locking relation to the abutment 70 on the slide 14. In order to yieldably retain the locking button 72 in either the locked or the unlocked position, a spring 80 is provided, the free end whereof projects into the path of movement of the button 72 at an intermediate point thereof. The spring 80 thus acts to either yieldably retain the button

72 in the lower locked position or in a raised unlocked position.

Considering the operation of the device as a whole, it will be appreciated that the parts are shown in the normal locked position thereof, with the bolt projected, and with the locking roller 72 in the lower or locked condition. With the parts thus positioned, the roller 72 lies in blocking relation to the projection 70, so that the slide 14 is prevented from being moved in a retracting or rightward direction. Thus, both the outside rollback 16 and the inside link 18 are ineffective to cause a retracting movement of the bolt 12. Assuming it is desired to release the locking device, and render the outside and inside handles effective for operation, the control rod 78 may be drawn upwardly, moving the roller 72 from the locking position shown in Fig. 1 to the upper or unlocked position in which it is out of blocking relation to the path of movement of the abutment 70.

With the locking device thus released, the inside link 18, for example, may be actuated to the right, as viewed in Fig. 1, in which event the roller 82, secured at the end thereof abuts the end of the slot 84 formed in the end of the slide 14, and causes a corresponding movement to the right of the slide 14. The movement to the right of the slide 14 is communicated to the bolt 22 by means of the rubber buffer 40, which bears against the previously mentioned foot 38 formed on the lower part of the bolt body. A corresponding action may be effected by rotating the outside rollback 16 in a clockwise direction by a corresponding rotation of the spindle 46. The clockwise rotation of the outside rollback 16 causes the nose 48 thereof to bear against the foot 50 formed on the slide and force the latter to the right. It will be seen, accordingly, that upon release of the locking device 20, either the outside rollback or the inside link may be actuated to move the slide 14 to the right and cause a corresponding rightward or retracting movement of the bolt 22.

Assuming the inside handle or the outside rollback is released, as the case may be, the coil spring 66, associated with the slide 14, becomes effective to force the latter to the left to its illustrated normal position, thus either returning the link 18 to the normal position or returning the rollback 16 to the normal position. Assuming that the nose 22 of the bolt is not blocked from movement by the lock-keeper (not shown) at the time the inside handle or the outside handle is released, the spring 26 associated therewith becomes effective to force the bolt 12 leftward to its projected position, which movement, through the engagement of the foot 38 with the buffer 40, assists the restoring movement of the slide 14.

It will be noted that the bolt 12 may be retracted independently of the position of the slide 14, by the application of pressure to the nose thereof, such for example as results from a normal closing movement of a door. Under such conditions, the bolt 12 moves to the right against the force of the compression spring 26, moving the foot 38 to the right away from the rubber buffer 40. Under these conditions, the slide 14 remains in its normal position, in which it is effective to hold the outside rollback 16 in wedging relation to the spindle 46.

A feature of the present invention resides in arranging the bolt so that a retracting movement thereof under the just-mentioned conditions,

serves to move the locking device 20 from the locking position shown in Fig. 1 to the unlocked position thereof. This feature is of importance primarily in that it prevents the operator of the associated vehicle from inadvertently setting the locking device 20 into locking position while the door is open and thereafter closing the door, leaving both the inside and outside handles locked against actuation. Assuming that the locking device 20 is set into operative position while the bolt is projected, and that the bolt is thereafter retracted as by closing movement of the door, it will be noted that the angled face 86 of the bolt in moving to the right, engages the lower side of the roller 72, so that continued movement of the bolt to the right cams the roller 72 upwardly to the unlocked position thereof, in which unlocked position it is yieldably retained by the detent spring 80.

In the modified embodiment of the invention shown in Figs. 3, 4 and 5, the bolt 100 is provided with a thickened nose 102, and a rearwardly and downwardly offset body portion 104. The nose of the bolt is guided in the opening provided therefor in the flange 106 of the case plate 108, and the body 104 thereof is guided by a pin 110, which rides in an elongated slot 112 provided in the bolt body. A coil spring 114 is provided, the free end whereof bears against the shoulder constituted by the rear edge 116 of the bolt head, and so continuously urges the bolt 100 to the leftward or to the fully projected position. The rear end 117 of the bolt body is extended upwardly and is provided with a laterally turned foot 118, which normally abuts the outer end of a rubber buffer 120, which is held in place between the base 122 of the case plate and a supplemental casing member 124, which is secured to the base of the case plate. The previously mentioned pin 110 is, of course, secured between the supplemental casing member 124 and the base 122 of the case plate.

The retracting slide 130, which corresponds generally to the previously described slide 14 and responds to the outside rollback mechanism 132 and the inside link 134 in a similar manner, is provided with a longitudinally extending body, which lies adjacent the case plate base 122. The slide 130, upon being moved to the right, causes corresponding rightward movement of the bolt 100 through the engagement of a shoulder 136 formed thereon with an inwardly turned foot 138 formed on the bolt 100. The slide 130 is guided relative to the casing 128 by means of the guide pin 110 which rides in a corresponding slot formed therein, and also by a tongue 140, which extends between the body of a supplemental casing member 142 and the base 122 of the case plate. As in the case of the above-described embodiment also, the casing member 142 which is conventionally secured to the case plate, also acts as a bearing support for the outside operated rollback element 144. The slide 130 is provided with a coil spring 146 which acts against the projection 148 thereon which extends downwardly therefrom, and so continuously urges the slide 130 to the left to the position shown in Fig. 3. To adapt it for cooperation with the locking device, designated as a whole as 150, the slide 130 is provided with an upwardly extending projection 152.

In the present instance, the locking device 150 comprises a slide 154, which is guided with respect to the base 122 of the casing by means of a clip 155, which embraces the body of the slide, 75

and by the locking pin 158. The clip 155 is secured to the case plate by a guide pin 156, and is received in a slot 157 formed in the slide. The pin 158 has a reduced portion which rides in an elongated slot 160 formed in the base 122 of the case plate. The lower end of the slide 154 is disposed, when in the lower or locking position thereof, to lie in blocking relation to the projection 152 on the slide 130.

In order to yieldably hold the slide 154 in either the lower locked position or a raised unlocked position, between which positions it may be moved by the control rod 164, the previously mentioned clip 156 is provided with a downwardly extending spring tongue 166, the lower end whereof is provided with an inwardly projecting rounded boss 168. The boss 168 is disposed to be releasably received in either the guide slot 170 or a lower opening 172, both of which are formed in the slide 154. When the slide 154 is in the lower locked position, the boss 168 is received in the slot 170. When, however, the control rod 164 is actuated in an upward direction, the boss 168 is forced out of the slot 170 and, when the slide 154 reaches its upper position, snaps into the lower opening 172 formed in the slide. As in the previous embodiment, the body of the bolt is provided with an angled surface 174, which bears against the head of the pin 158 and acts to cam the pin 158 and the slide 154 from the lower locking position to an upper unlocked position thereof, in response to a reTRACTING movement of the bolt 100.

In all other respects except those described, both as to structure and operation, the embodiment of Figs. 3, 4 and 5 may correspond to that of the embodiment of Figs. 1 and 2. It is thought, therefore, that no further description of the embodiment of Figs. 3, 4 and 5 is needed.

Although specific embodiments of the present invention have been described in detail, it will be appreciated that such embodiments are illustrative only and that various modifications in the form, number and arrangement of the parts may be made within the spirit and scope of the present invention.

What is claimed is:

1. In a latch for association with a closure member and a cooperating member, the combination of a bolt carried by one of the members and releasably engageable with a keeper carried by the other member and movable by the keeper as an incident to a closing movement of the closure, first and second operators respectively operable from within and without the closure for releasing the bolt, means including a single manually operable locking member common to said operators and actuatable to render both said operators ineffective to release said bolt, and means actuated by said movement of the bolt by the keeper for restoring said locking member to unlocked condition.
2. In a latch for association with a closure member and a cooperating member, the combination of a bolt slidably carried by one of the members and retractably engageable with a keeper carried by the other member, said bolt being movable by the keeper as an incident to a closing movement of the closure, a retracting member carried by said one of the members and actuatable to release the bolt, first and second operators respectively operable from within and without the closure for actuating the retracting member, means including a single manually op-

erable locking member common to said operators and actuatable to render both said operators ineffective to retract said retracting member, and means actuated by said movement of the bolt by the keeper for restoring said locking member to unlocked condition.

3. In a latch for association with a closure member and a cooperating member and having a casing carried by one of the members, the combination of a bolt slidably supported on said casing for movement between a projected and a retracted position, a retracting member actuatable to effect a retracting movement of the bolt, inside and outside handle operated means operable to actuate said retracting member, and means comprising a member projecting from the casing and common to said bolt and retracting member for guidably supporting the same on the casing.

4. In a latch for association with a closure member and a cooperating member and having a casing carried by one of the members, the combination of a bolt slidably supported on said casing for movement between a projected and a retracted position, a retracting member actuatable to effect a retracting movement of the bolt, inside and outside handle operated means operable to actuate said retracting member, a pin common to said bolt and retracting member for guidably supporting the same on the casing and having one end secured in the casing, a deck secured to the casing in spaced relation thereto for supporting the other end of the pin, and means comprising a locking member guidably supported between the deck and the casing and movable into a position to block movement of the retracting member.

5. In a latch for association with a closure member and a cooperating member and having a casing carried by one of the members, the combination of a bolt slidably supported on said casing for movement between a projected and a retracted position, a retracting member actuatable to effect a retracting movement of the bolt, inside and outside handle operated means operable to actuate said retracting member, a pin common to said bolt and retracting member for guidably supporting the same on the casing and having one end secured in the casing, a deck secured to the casing in spaced relation thereto for supporting the other end of the pin, means comprising a locking member guidably supported between the deck and the casing and movable into a position to block movement of the retracting member, and means rendering a retracting movement of

the bolt effective to restore said locking member to unlocked position.

6. In an automobile door latch, a bolt member, inside and outside operators including an inside reciprocating link and an outside roll back arm, means for operatively connecting said inside link and said outside roll back arm to said bolt member to enable said link and arm to render the bolt member ineffective to restrain the door, a single control device normally in a position where it is disconnected from said means but adapted to be moved through a path arranged at right angles to the roll back axis into a position where it will operate to prevent movement of said means and thereby prevent the inside link and the outside roll back arm from so rendering the bolt member ineffective, a single spring for holding the control device in both of said positions, and means operated by slamming of the door to move the single control device into its normal position where it is disconnected from said means.

7. In a door latch, a bolt, inside and outside operators, a first member responsive to said inside operator and a second member responsive to said outside operator, means for operatively connecting said first and second members to said bolt to enable said operators, respectively, to render the bolt ineffective to restrain the door, a single control device normally in a position in which it is ineffective but adapted to be moved into a position where it will operate to prevent the said inside and outside operators from so rendering the bolt ineffective, means for releasably holding the control device in each of said positions, and means operated by a closing of the door to move the single control device into its normal position.

8. In a door latch, a movably mounted bolt, inside and outside operators, a first member responsive to said inside operator and a second member responsive to said outside operator, means for operatively connecting said first and second members to said bolt to enable said operators, respectively, to render the bolt ineffective to restrain the door, a single control device normally in a position in which it is ineffective but adapted to be moved into a position where it will operate to prevent the said inside and outside operators from so rendering the bolt ineffective, means for releasably holding the control device in each of said positions, and means operated by movement of said bolt for restoring the locking device to its normal position.

ROLLO MARPLE.
